THOMAS F. CROCKER, OF CHICAGO, ILLINOIS, ASSIGNOR TO RESERVE HOLDING COMPANY OF KANSAS CITY, MISSOURI, A CORPORATION OF DELAWARE

PRIVATE AUTOMATIC EXCHANGE SYSTEM

Application filed February 29, 1928. Serial No. 258,108.

This invention relates to telephone systems in general, but is more particularly concerned with small automatic telephone systems commonly known as private automatic exchange systems in which an attendant is employed to complete certain connections.

The object of this invention is the provision of a new and improved attendant's cord circuit and a new and improved associated trunk circuit, particularly designed for use in a private automatic exchange connected by two-way trunk lines with a main exchange.

The cord circuit of this invention is of the type having a cord-splitting key by means of which the attendant, after setting up a connection to a called subscriber's line at the request of a calling subscriber, may converse with the called subscriber without the calling subscriber hearing the conversation. A particular feature of this invention is the provision of means in the cord circuit which requires the attendant to press a special connect key before the actual talking circuit between the called and the calling subscriber can be established, though she may converse with either separately before operating the special connect key.

Another feature of this invention is that should the attendant not care to converse with the called subscriber separately before completing the talking connection between the calling and the called subscriber, she may operate the special connect key immediately so that the talking connection between the calling and the called subscriber will be automatically completed as soon as the called subscriber answers.

Another feature of this invention is that after a connection has been set up and the called party has hung up his receiver, no talking connection can again be completed with the first calling party, should the called party again remove his receiver, until the special connect key is again operated.

Another feature of this invention resides in

the arrangement for preventing the application of ringing current on a busy line or a called line after the called subscriber has answered, or for preventing any interference with the setting up of a connection, should the attendant insert the plug of her cord into a busy line jack and attempt to ring, or attempt to ring after a called subscriber has answered, or insert the plug of her cord into a busy trunk jack and attempt to dial out.

Another feature of the invention is the manner in which a trunk line extending to a main exchange is marked busy at the private automatic exchange when the trunk is taken for use at the main exchange. The trunk is marked busy by a high resistance relay at the private automatic exchange, which is connected to one conductor of the trunk line and to ground. This relay is energized when the trunk is first seized in series with the ring cut-off relay of the connector seizing the trunk at the main exchange, and is energized in series with the back-bridge relay of the connector, if the trunk is held from the main exchange after it has been released at the private automatic exchange.

The above mentioned features and others not particularly mentioned at this time will be described in detail in the following specification with the aid of the accompanying drawings comprising Figs. 1 and 2. These drawings, when Fig. 2 is placed to the right of Fig. 1, illustrate by means of the usual circuit diagrams a schematic layout of a private automatic exchange system connected by means of two-way trunk lines with a main automatic exchange.

The apparatus shown in Fig. 1, and that shown to the left of the dotted vertical line in Fig. 2, is in the private automatic exchange, designated P. A. X., while that shown to the right of the dotted vertical line in Fig. 2, is located in the main automatic exchange, designated M. A. X. The trunk comprising conductors 201 and 202 is one of the trunks con-

necting the P. A. X. with the M. A. X. At the M. A. X. this trunk terminates in the rotary lineswitch LS² and is accessible to a group of connectors, such as connector C². The lineswitch LS² is of the usual rotary type. It has access to incoming selectors (not shown). The connector C² (shown only in skeleton) may be of the usual Strowger vertical and rotary type, having an automatic rotary movement on the level in which the inter-office trunk lines are accessible. A connector of this type is shown and described in the Jacobson Patent No. 1,349,381, granted August 10, 1920. In the system chosen to illustrate this invention the main exchange, is assumed to be an automatic exchange, though the private automatic exchange is equally capable of being connected with a manual main exchange.

At the P. A. X. the trunk comprising conductors 201 and 202 terminates at the attendant's cabinet in the jack J² and is provided with a call lamp L² and a busy visual VIS.

The cord CC is one of a plurality of cord circuits provided for the attendant for completing calls from the M. A. X. for subscribers at the P. A. X. This cord circuit terminates in the plugs P and P' and is provided with a connect and ringing key RK, and a cord key CK for associating the operator's telephone set TS and the common equipment comprising the telephone set relays TSR, the cord splitting key CSK, the dial key DK, and the dial D with this particular cord.

One of the private automatic exchange subscribers' lines, namely, the line of substation A, is shown, terminating in the lineswitch LS and having the individual line jack J. The lineswitch LS may be of the usual rotary type like the rotary lineswitch LS². This lineswitch has access with other similar lineswitches to a group of selectors such as the selector S. The selector S may be of the usual Strowger vertical and rotary type, and has access to a number of groups of connectors, such as connector C.

In one particular level the selectors such as selector S have access to the M. A. X. and in another level to key-ending trunks extending to the attendant's position. In the banks of the connectors access is had to the individual subscribers' lines.

With this general description of the features of the invention and the apparatus involved in mind, a further understanding of the invention may best be gained from a detailed description of the operations involved in completing connections. For this purpose it will first be assumed that a subscriber at the M. A. X. wishes to converse with the subscriber at substation A. It will be assumed that the calling subscriber has extended the connection to the connector C² which has been operated to seize the trunk to the P. A. X. via the branch comprising conductors

201' to 203'. When this trunk is seized, the switching relay 245 of the connector C² and the cut-off relay 210 of the lineswitch LS² energize in series. Relay 210, in operating, disconnects the normal ground and battery connections from the trunk conductors by separating contacts 211 and 218 in the usual manner.

After relay 245 of connector C² is operated, a circuit is closed for the busy guard relay 110, at the P. A. X. which includes contacts 101, conductor 201, conductor 201', and the upper winding of the ring cut-off relay 250 of the connector C². The resistance of relay 110 is sufficiently high to prevent a sufficient flow of current in this circuit to cause the operation of the ring cut-off relay 250 at this time. Relay 110 at the P. A. X. operates, however, and closes the circuit for the busy visual VIS at contacts 111 to mark this trunk busy at the attendant's position and also closes a circuit for relay 115 at contacts 112. Relay 115 operates and at contacts 116 grounds the release conductor 206 to mark the trunk busy to the selectors.

Relay 245 of connector C², in operating, also causes ringing current to be intermittently applied to the trunk conductors, causing the operation of the ringing response relay 106 bridged across the trunk conductors at the P. A. X. Relay 106, in closing contacts 107, closes a locking circuit for its lower winding and also closes a circuit for the call lamp L². The lighting of lamp L² apprises the attendant of the incoming call.

To answer the call, the attendant inserts the answering plug of an idle cord, such as plug P' of cord circuit CC, into jack J². As a result, relay 30 and relay 100 operate in series. Relay 100, in operating, disconnects relays 110 and 106 from the upper talking conductor at contacts 101, closes an auxiliary circuit for busy visual VIS at contacts 103, at the same time opening the holding circuit of relay 106 and the circuit of lamp L² by separating contacts 102, and short-circuits the condenser 108 at contacts 104. By short-circuiting the condenser 108 it is discharged. Discharging the condenser at this time eliminates the possibility of relay 106 being operated and locking at the end of the call when the ringing bridge is again placed across the trunk conductors upon the removal of plug P' from jack J².

Relay 110 restores as soon as it is disconnected from the upper trunk conductor, opening the initial circuit of the visual VIS and the circuit of relay 115. Relay 115 restores after which the trunk is marked busy by the presence of ground through the low resistance winding of relay 30 via contacts 117.

Relay 41 also operates when the plug P' is inserted in the jack J² from ringing current passing through its lower winding. This relay, in operating, closes a locking circuit for its upper winding at contacts 42, at the

same time closing a circuit for the supervisory lamp L¹.

After inserting the plug P' into jack J², the attendant operates the cord key CK. As a result, relay 24 operates over the circuit including contacts 82 and 81. This relay connects the common talking conductors 71 and 72 to the cord conductors 93 and 94 at contacts 27 and 28 and places a direct current bridge 10 across condenser 99 at contacts 25, contacts 32 being closed. The operation of key CK also closes a circuit for relay 35 in series with relay 50, the circuit including contacts 83. The short-circuit around relay 35 is opened 15 by the operation of relay 30 at contacts 33. Relay 35, in operating, opens the circuit of lamp L¹ and the holding circuit of relay 41 at contacts 38, and connects the common conductors 74 and 75 to the tip and ring conductors of plug P'. A ring-trip bridge has now been closed across the trunk conductors for causing the operation of ring cut-off relay 250 in the connector C2, which extends from the tip of plug P', contacts 36, conductor 75, 25 upper normally closed contacts of keys DK and CSK, conductor 71, contacts 87 and 27, the upper right hand winding of repeating coil R contacts 25 and 32, the lower right hand winding of repeating coil R, contacts 28 and 30 88, conductor 72, lower normally closed contacts of keys CSK and DK, conductor 74, contacts 39, to the ring of plug P'. Relay 250 therefore operates and trips the ringing in the usual manner and closes points in the talking connection. The back-bridge 255 then operates over the two trunk conductors and the bridge across the tip and ring of plug P' with the usual results.

Relay 50, in operating in series with relay 40 35, opens a point in the receiver circuit at contacts 51 and closes a circuit for relay 55 at contacts 52. Relay 55 operates and closes a point in the receiver circuit at contacts 56, closes a holding circuit for itself at contacts 45 57, and disconnects relay 50. Shortly after its circuit is opened, relay 50 deenergizes and by closing contacts 51 closes the receiver circuit. Thereafter relay 55 is held energized in series with relay 35. By so delaying the closure 50 of the receiver circuit until some time after the ring is tripped and the current over the trunk conductors has become steady, annoying clicks in the receiver are prevented.

The attendant may now converse with the 55 calling subscriber at the main automatic exchange to learn the name of the subscriber with whom connection is desired. After obtaining this information, the attendant touches the tip of the plug P' to the sleeve of jack J (having assumed that the subscriber at substation A is the called subscriber) to test the line for the busy or idle condition in the usual manner. Finding the line idle, the attendant inserts plug P into jack J. Relay 60 2 operates in series with the cut-off relay 97

of the lineswitch LS, closing points in the talking circuit at contacts 4 and 6, and closing the circuit of the supervisory lamp L at contacts 5.

After inserting plug P into jack J, the attendant operates key RK to the right to project ringing current out on the called subscriber's line. The ringing circuit includes contacts 14 and 19, and contacts 4 and 6.

When the subscriber at substation A answers by removing his receiver, a circuit is closed for battery feed relay 10. Relay 10, in operating, opens the circuit of lamp L at contacts 11 and prepares a circuit for relay 15 at contacts 12. The extinguishment of lamp L notifies the attendant that the called subscriber has answered.

Before completing the talking connection with the calling subscriber, the operator may converse with the called subscriber to learn what disposition to make of the call without the calling subscriber hearing the conversation. To do so, the attendant operates the common cord splitting key CSK to the right. This operation disconnects the common leads 74 and 75 from the operator's talking conductors 76 and 77, and at contacts 84 places a holding bridge including resistance 85 across the tip and ring conductors. Operating key CSK to the right also opens the circuit of relay 24 at contacts 81. Relay 24, in deenergizing, connects the common talking leads 71 and 72 on the tip and ring conductors of plug P at contacts 26 and 29 via contacts on the ringing key RK. The attendant may now speak with the subscriber at substation A without the calling party hearing the conversation. If the subscriber at substation A does not wish to speak with the calling subscriber, the attendant by again restoring key CSK, may inform the calling subscriber that the subscriber at substation A is not available at this time.

If the subscriber at substation A wishes the connection completed, however, the attendant needs merely to operate the key RK momentarily to the left and then restore the key CK to disassociate her head set and common apparatus from the cord circuit CC. Operating key RK momentarily to the left closes a circuit for relay 20. Relay 20 energizes and closes a holding circuit for relay 24 at contacts 23, closes a point in talking connection at contacts 22, and closes a holding circuit for itself in series with relay 15 at contacts 21. Relay 15 operates and at contacts 16 and 18 completes the talking circuit, and by separating contacts 14 and 19 disconnects the operating springs of the ringing key RK from conductors 95 and 96. The calling and called subscribers may now converse with each other. Before key CK is restored, the talking circuit extends through the springs of keys CSK and DK. When key CK is restored, the circuit of relay 35

70

95

100

105

110

115

120

125

130

and relay 55 is opened at contacts 83. Relay 55 in restoring, places the telephone set relays TSR in their normal condition. Relay 35, in deenergizing, connects the talking conductors 93 and 94 to the tip and ring of plug P' directly, thereby completing the talking circuit between the calling and the called subscriber independent of keys CSK and DK.

It is to be noted that should the operator in the case of an emergency wish to talk to either party to the exclusion of the other after the talking connection between them has been completed, she may do so by again associating the common equipment including key CSK with the cord circuit CC by operating the cord key CK, and then operating key CSK to the right or left depending on which party she wishes to speak with. Throwing key CSK to the left disconnects the common talking conductors 71 and 72 from the operator's talking conductors 76 and 77, and also opens points in the holding circuit across the tip and ring of plug P' extending through the springs of key CSK whenever key CK is operated, but a substitute one is provided through the secondary windings of the operator's induction coil when condenser 78 is short-circuited at contacts 86.

At the termination of the conversation both subscribers will replace their receivers. Responsive to the replacement of the receiver at substation A, relay 10 restores thereby opening the circuit of relays 15 and 20 at contacts 12, and closing the circuit of supervisory lamp L at contacts 11. Relay 15, in deenergizing, again opens the talking circuit at contacts 16 and 18. Relay 20, in deenergizing, opens the holding circuit of relay 24. Relay 24 deenergizes and at contacts 25 opens the direct current bridge across the tip and ring conductors of P' thereby opening the circuit of back-bridge relay 255 of connector C² at the main automatic exchange. The release of back-bridge relay 255 in the well known manner causes the release of the connector C², providing the calling subscriber has previously replaced his receiver. If the calling party, however, does not replace his receiver, the connector C², as well as the other automatic switches used in the connection, will not be released until he does so, as is well known.

Should the called subscriber again remove his receiver after he has hung up, even though the plugs P and P' are in jacks J and J' and the calling subscriber is still holding the connection to the P. A. X. no talking connection can again be completed since relays 15 and 20 are deenergized. Of course, if the attendant again operated key RK to the right the talking connection would be completed as previously described.

The lighted condition of the lamp L after conversation has taken place indicates to the attendant that the conversation is terminated.

She will then remove the plugs P and P' of the jacks J and J'. Removing the plug P' from jack J' opens the circuit of relays 30 and 100. Relay 30 in deenergizing places the cord circuit CC in normal condition. Relay 100 in deenergizing again places the trunk to the main exchange in normal condition. If, however, the calling subscriber is still holding the connection, relay 110 will again operate, this time in series with the upper winding of back-bridge relay 255 of connector C². Relay 110 will again function to operate the busy visual VIS, and mark the trunk busy to the selectors.

As noted above, the trunk is marked idle at the M. A. X. as soon as both the calling and the called party replace their receivers. For this reason a second call can be extended from the main automatic exchange to the private automatic exchange over the trunk comprising conductors 201 and 202 before the attendant has removed plugs P and P' from jacks J and J' after the termination of a call. In such a case the connector seizing the trunk causes the operation of relay 110 and projects ringing current over the trunk conductors as previously described. Again relay 41 responds, closing the circuit for lamp L' and a holding circuit for its upper winding at contacts 42. The lighting of the lamp L' at this time notifies the attendant that a second call has come in over the trunk, while the lighted condition of lamp L indicates to her that the previous connection has been released. It should be particularly noted that ringing current over the trunk conductors at this time cannot resign the subscriber at substation A in whose jack the plug P rests, since the talking connection to the subscriber at substation A was opened upon the release of relay 15. The attendant may now answer the second call in the regular manner. The presence of plug P in jack J has no effect. After learning the wants of the calling subscriber she may remove the plug P from jack J and insert it into the proper jack and call the called subscriber as previously described.

If the attendant, after receiving an incoming call from the main automatic exchange knows that the called subscriber is waiting for a call from this particular calling subscriber, it is unnecessary for her to first speak with the called subscriber. She may call the called subscriber by operating the ringing key RK to the right (having set up the connection to the called line by inserting the plug P into the jack J) and immediately operate the key RK to the left momentarily before the called subscriber answers. The operation of key RK to the left prepares the cord circuit CC in such a way that the talking connection will be established as soon as the called subscriber removes his receiver. This operation closes the circuit for relay 20

which again operates and closes a locking circuit at contacts 21, this time over a circuit including contacts 13, 17, and 5, relay 10 not being energized because the called subscriber has not yet answered. After operating the key RK to the left momentarily, the attendant may disassociate her common equipment including her telephone set from the cord circuit CC by restoring key CK and attend 10 to other calls. When the called subscriber answers, relay 10 again energizes and by closing contacts 12 again causes the operation of relay 15 in series with relay 20, with the results as previously described.

15 In this system it is also possible for any of the subscribers such as the subscriber at substation A to extend a call to the automatic exchange over one of the interconnecting trunk lines, these trunks being accessible in a particular level in the banks of the selectors. For example, when a call is extended from the substation A via the individual lineswitch LS and the selector S to the trunk line comprising conductors 201 and 202 by 25 way of the branch comprising conductors 204 to 206, the lineswitch LS² operates in the usual way and extends the connection to a selector in the main automatic exchange. When the trunk line is seized, ground potential is placed on release conductor 206 thereby closing a circuit for relay 100. Relay 100 30 operates and disconnects the ringing bridge from across the trunk conductors at contacts 101 and 105 and closes a circuit for the busy 35 visual VIS at contacts 103. Relay 125 also operates in series with the trunk conductor 201 and at contacts 126 closes a circuit for release relay 120. Relay 120 directly grounds release conductor 106 at contacts 121 to maintain the automatic switches in the P. A. X. 40 operated and maintain this trunk marked busy. The subscriber at substation A, by dialing the proper number controls the setting up of the connection in the usual manner.

45 When the subscribers replace their receivers at the termination of the call, the operated automatic switches at the P. A. X. and the M. A. X. release, and relays 125, 120, and 100 restore in the order named.

50 The subscribers at the P. A. X. may also call to the attendant for information purposes over a special key ending trunk such as the one comprising conductors 271 to 273 also accessible to the selectors. For example, when a call is extended from the substation A via lineswitch LS and selector S to the trunk comprising conductors 271 to 273, relay 270 operates and closes a circuit for relay 265 at contacts 271, and closes the circuit for 55 lamp L³ at contacts 272. The lighting of the lamp L³ indicates to the attendant that some information is wanted. To answer the call the attendant operates key K². As a result relay 260 is operated over the circuit including contacts 281. The lamp L³ is ex-

tinguished. At contacts 282, a circuit is closed for relay 65 of the telephone set relays TSR. Relay 65, in energizing, connects the telephone circuit to the common conductors 291, 292, and 293. At contacts 68, a circuit is also closed for relay 50 which energizes and causes the energization of relay 55, with the results previously described.

In the system disclosed, an attendant may also set up a so-called tail-to-tail connection; that is, should she be asked by one of the P. A. X. subscribers to set up a connection for him to the M. A. X. she may insert the plug P' into the jack of an idle trunk extending to the main automatic exchange, such as the jack J2 for example, then operate the corresponding cord key CK, then operate the common dial key DK, and then dial the desired number. Inserting the plug P' into jack J² again closes a circuit for relays 30 and 100 in series. These relays operate, performing the same circuit changes as previously described. The operation of key CK closes a circuit of relay 35 which operates and connects conductors 74 and 75 to the tip and ring of plug P'. Operating the dial key DK bridges the dial D across conductors 74 and 75. Lineswitch LS² operates and extends the connection to a selector in the usual manner. This selector and other automatic switches in the main automatic exchange respond to the manipulations of the dial D in accordance with the called subscriber's number to extend the connection to the called line.

After setting up the connection to the called subscriber the attendant may call the P. A. X. subscriber who requested the connection in the same manner as though the call had been initiated by the called subscriber at the main automatic exchange. In this case, she may also operate the key RK momentarily to the left immediately and disassociate the common equipment from the cord circuit by restoring key CK before either the calling or called party has answered, or she may converse with the P. A. X. subscriber after he answers without the other party hearing the conversation the same as previously described.

A particular characteristic of this invention is that should an attendant attempt to extend a call to a P. A. X. subscriber already busy in another connection or engaged in the process of setting up a connection, the plugging in of the plug of a cord into his line jack will not interfere with the existing connection or with the setting up of the other connection. For example, should the attendant insert plug P into jack J (ignoring the busy test while the subscriber at substation A is engaged in setting up automatic switches in the P. A. X., relay 2 could not operate since direct ground potential would be present on the sleeve of jack J. In this

case lamp L would not light which would further indicate to the attendant that the line was busy. Even if she also ignored this indication and attempted to ring by operating key RK to the left, no ringing current could be projected out on the connection by reason of the open condition of contacts 4 and 6.

It is also impossible for the attendant to project ringing current on the called line after the talking connection between the calling and called subscriber has been completed. When relay 15 operates and completes the talking connection, the ringing leads are disconnected from conductors 95 and 96 at contacts 14 and 19. Thereafter any operation of key RK is ineffective.

Furthermore, the attendant can not interfere with the setting up of a connection to the main exchange by the calling P. A. X. subscriber by inserting plug P' into the jack of the trunk extending to the main exchange over which the connection is being set up. For example, should the attendant insert plug P' into jack J² while the subscriber at substation A is engaged in the process of setting up a connection to the main automatic exchange over the trunk comprising conductors 201 and 202, no harm would result. Since ground potential would be present on jack J², relay 30 could not operate in series with relay 100. With relay 30 remaining in a deenergized position relay 35 would remain short-circuited at contacts 33 so that throwing cord key CK and the dialling key DK would not bridge the dial D across the tip and ring of plug P'. By relay 35 remaining in a deenergized condition the tip and ring of plug P' remain connected to conductors 93 and 94. Throwing key CK would, however, cause the operation of relay 24 and the operation of relays 50 and 55 as previously described. The attendant's head set would then be bridged across the tip and ring of plug P' so that she would be advised of her error by hearing clicks produced by the dialling operation or by hearing the conversation.

This completes the description of the operation of the invention. What is considered new and is desired to have protected by Letters Patent is specifically stated in the appended claims.

What is claimed is:

1. In a telephone system, a line, a cord circuit comprising two normally disconnected sections, means for connecting said cord circuit to said line to extend a call, a key, and means responsive to a momentary operation of said key after the call is answered for connecting said sections.

2. In a telephone system, a line, a cord circuit comprising two normally disconnected sections, means for connecting said cord circuit to said line to extend a call, a self-locking

relay in said cord, means operable at will for operating said self-locking relay, a second relay responsive to the answering of the call, and means for connecting said sections jointly controlled by said self-locking relay and said second relay. 70

3. In a telephone system, a line, a cord circuit comprising two normally disconnected sections, means for connecting said cord circuit to said line to extend a call, a key, means responsive to a momentary operation of said key after the subscriber at the station on the line has removed his receiver to answer the call for connecting said sections, and means responsive to the replacement of the receiver for deactuating said last means so that it cannot again be operated should the receiver again be removed until said key is again operated. 75 80

4. In a telephone system, a line, a cord circuit comprising two normally disconnected sections, means for connecting said cord circuit to said line to extend a call, a key, and means responsive to the answering of the call providing said key is operated before the call is answered, and responsive to the operation of said key providing the call is answered before the key is operated, for connecting said sections. 85 90

5. In a telephone system, a line, a cord circuit comprising two normally disconnected sections, means for connecting said cord circuit to said line to extend a call, means for signalling the subscriber on said line, key springs, and means responsive to a momentary operation of said key springs after the call is answered for connecting said sections and for disabling said signalling means. 95 100

6. In a cord circuit comprising two normally disconnected sections, a ringing key and leads extending from said key to the talking strands of the cord circuit, a relay for connecting said two sections, and contacts on said relay for disconnecting said leads from said talking strands. 105 110

7. In a telephone system, a cord circuit having a first and a second plug, a pair of talking conductors having two branches, means for connecting the first branch to the first plug, means for disconnecting the first branch from the pair of talking conductors, and means responsive to said last means for connecting said second branch to said second plug. 115

8. In a telephone system, a cord circuit, a pair of talking conductors having two branches, a key in said cord, connecting means responsive to the operation of said key under certain conditions for connecting the first branch to one end of said cord circuit, means for maintaining said connecting means inoperative if said certain conditions do not obtain, and means responsive to the operation of said key for connecting the second branch to said one end of said cord circuit. 120 125 130

cuit, providing said connecting means are maintained inoperative.

9. In a telephone system, a plug ending cord circuit, a jack ending trunk, a pair of talking conductors, a pair of control conductors, a key, and means responsive to the operation of said key after the plug of said cord is inserted into said jack for connecting said control conductors to said plug, providing said trunk is idle, and for connecting said talking conductors to said plug, providing the trunk is busy.

10. In a telephone system, a first exchange, a second exchange, an interconnecting trunk line, a switch at said second exchange having access to said trunk, a ring cut-off relay in said switch, a busy guard relay at said first exchange connected to one conductor of said trunk line and to ground, and energized in series with said ring cut-off relay responsive to the seizure of said trunk line by said switch in the extension of a call to said first exchange, means controlled by said busy guard relay for marking said trunk line busy 15 at said first exchange, a ringing bridge including a ringing relay across the conductors of said trunk line at said first exchange, means in said switch for projecting ringing current on the trunk conductors to operate 20 said ringing relay to signal an attendant at said first exchange, and means responsive to the answering of the call for disconnecting said busy guard relay, for opening said ringing bridge, and for operating said ring cut- 25 off relay.

11. In a telephone system, a first exchange, a second exchange, a connector at said second exchange, an interconnecting trunk line accessible to said connector at said 30 second exchange, a ring cut-off relay and a back-bridge relay in said connector, a busy guard relay at said first exchange connected to a conductor of said trunk line and energized in series with said ring cut-off relay responsive to the seizure of said trunk by said connector to extend a call to said first exchange, means for disconnecting said busy guard relay from said conductor and for operating said ring cut-off relay when the call is answered and for reconnecting said busy guard relay to said conductor at the termination of the call, said busy guard relay being energized in series with said back-bridge relay upon its reconnection to said 35 conductor, and means controlled by said busy guard relay for marking said trunk line busy at said first exchange.

12. In a telephone system, a first exchange, a second exchange, an interconnecting trunk line, one conductor of said trunk being normally connected to ground at said second exchange, a busy guard relay at said first exchange connected to said one conductor and to ground, an automatic switch at 40 said second exchange having access to said

trunk line, a battery having one pole connected to ground, a ring cut-off relay in said switch connected to the ungrounded pole of said battery, means responsive to the seizure of said trunk by said switch in the extension of a call to said first exchange for disconnecting said normal ground connection from said one conductor and for connecting said ring cut-off relay to said conductor to cause the operation of said busy guard relay, means controlled by said busy guard relay for marking said trunk busy at said first exchange, and means responsive to the answering of the call for disconnecting said busy guard relay and for operating said ring cut-off relay to complete the talking connection.

13. In a telephone system, a trunk line, a bridge including a relay and a condenser in series connected across the conductors of said trunk line, means for extending a connection over said trunk line and for projecting ringing current over the conductors of said trunk line to operate said relay, means for disconnecting said bridge from said conductors and for short-circuiting said condenser when the call is answered, and for reconnecting said bridge across said conductors at the termination of the call.

14. In a telephone system, a trunk line, a bridge including a relay and a condenser in series connected across the conductors of said trunk line, means for extending a connection over said trunk line and for projecting ringing current over the conductors of said trunk line to operate said relay, a second relay for disconnecting said bridge when the call is answered and for reconnecting said bridge across said conductors at the termination of the call, and contacts on said second relay for short-circuiting said condenser when the call is answered to discharge the same to eliminate the possibility of said first relay being operated by a discharge of said condenser when the bridge is reconnected across said conductors.

15. In a telephone system, a cord circuit for answering and extending calls, a pair of talking conductors, a double-throw cord-splitting key for associating said talking conductors with either end of said cord circuit to the exclusion of the other, means responsive to the answering of a call for connecting a direct current bridge across the conductors of one end of said cord, said bridge including normally closed contacts on said key, other contacts on said key for providing a substitute direct current bridge including said talking conductors in series when said first bridge is opened by the operation of said key in one direction, a resistance, and other contacts on said key for providing a substitute direct current bridge including said resistance when said first bridge is opened by the operation of said key in the other direction.

16. In a telephone system, a cord circuit, a trunk accessible to said cord circuit, a pair of dialling conductors, a key, means controlled by said key for connecting said conductors to the cord circuit, provided said trunk is idle when connected with, and means effective in case the trunk is busy for rendering said means non-responsive to said key.
17. In a telephone system, a cord circuit, a trunk accessible to said cord circuit, a pair of dialling conductors, a key, means controlled by said key for connecting said conductors to the cord circuit, provided the trunk is idle when connected with, means effective in case the trunk is busy for rendering said means non-responsive to said key, and means controlled by said key for notifying the operator of the busy condition of said trunk.
18. In a telephone system, a two-way trunk, a connector switch for connecting with said trunk at one end, means in said connector for ringing over the trunk, means in said connector for establishing a direct current circuit over only one conductor of the trunk and for maintaining the same while the ringing operation is proceeding, and a busying relay at the distant end of the trunk controlled over said direct current circuit.
19. In a telephone system, a two-way trunk line, a connector for seizing said trunk at one end, two circuits established by said connector on seizing the trunk line, one circuit including both conductors of the trunk in series and a source of ringing current and the other circuit including only one conductor of the trunk and ground, a ring-cut-off relay in said connector included in both said circuits, and busying means at the distant end of the trunk controlled over said grounded circuit.
20. In a telephone system, a two-way trunk line, a connector for seizing said trunk line at one end, means in the connector for connecting a ringing current source to one conductor of said trunk line, a ring cut-off relay in said connector connected between the other conductor of the trunk and the exchange battery in readiness to cut off the ringing current when the call is answered, and busying means at the other end of the trunk line operated by current supplied over the said other trunk line conductor through the winding of said ring cut-off relay.
21. In a telephone system, a cord circuit for connecting a calling and a called line, a double-throw key in said cord circuit, means responsive to the operation of said key in one direction for transmitting ringing current over the called line, and means responsive to the operation of said key in the other direction after the called subscriber has answered for rendering said key ineffective in case it is reoperated in said first direction.
22. In a telephone system, a cord circuit

for extending a connection to a called line, a ringing key for transmitting ringing current over the called line, a relay controlled by the called subscriber, a second relay controlled by said ringing key, and means jointly controlled by said two relays for rendering said key ineffective.

In witness whereof, I hereunto subscribe my name this 21st day of February, A. D. 1928.

THOMAS F. CROCKER.
